NUMBER SELECTING GAME APPARATUS

Charles Benker, North Attleboro, Mass.

Application October 25, 1946, Serial No. 705,668

8 Claims. (Cl. 273—138)

1

The invention relates to a selector apparatus which may be utilized for playing games in which characters or numbers form part of the game and which characters or numbers are chosen by chance.

In the operation of certain amusement devices, some means is provided by which a player is notified whether or not a certain number appears in the game. There is some possibility of a person's missing hearing the number or misunderstanding the number, or otherwise being at fault in taking some action such as covering the number which appears, which human errors may disturb the game which is being played.

An object of this invention is to provide an apparatus wherein any one of a number of characters may be chosen by a moving element guided by chance.

Another object of this invention is to provide an apparatus which will positively indicate a number which has been chosen in the playing of the game, thus removing the chance of human fault, which may cause an error in the playing of the game.

Another object of this invention is to provide means by which the playing of the game may be made automatic with little chance of error.

Another object of this invention is to provide an apparatus wherein if a number has once appeared in the game, it cannot again appear until the game apparatus has been reset.

Another object of this invention is to provide a game which may be played more quickly by reason of the instantaneous indication to each player of the number which has been chosen.

Another object of this invention is to provide an arrangement whereby all of the playing boards which are used in the game will operate simultaneously as to any number should the number which is chosen appear on the board.

Another object of this invention is to provide an arrangement so that all of the boards may be reset to starting position once the game is completed.

Another object of this invention is the provision of an apparatus of this character wherein a free moving element when released, may be guided by chance to a position to be acted upon to actuate an indicating mechanism.

Another object of the invention is the provision of an apparatus of this character wherein a free rolling element when released, may be guided by chance to a position to be acted upon to actuate an indicating mechanism.

Another object of the invention is the pro-

2

vision of an apparatus of this character wherein a plurality of free moving elements upon being released in a consecutive order may be guided by chance to a position to be acted upon in an haphazard order with respect to the order of release thereof, to actuate a number indicating mechanism.

A more specific object of the invention is the provision of an apparatus of this character which can be manufactured at a comparatively low cost of production and which will be satisfactory in use.

With these and other objects in view, the invention consists of certain novel features of construction, as will be more fully described and particularly pointed out in the appended claims.

In the accompanying drawings:

Fig. 1 is a central sectional view of a game apparatus embodying my invention;

20 Fig. 2 is a view taken on line 2—2 of Fig. 1 showing a plurality of electric switches employed in the apparatus;

Fig. 3 is a perspective view of a closure element forming part of the invention;

25 Fig. 4 is a perspective view illustrating a closure element in one position thereof;

Fig. 5 is a perspective view of another detail;

Fig. 6 is a plan view of a fragment portion of the apparatus looking in the direction of the 30 arrows on line 6—6 of Fig. 1; and

Fig. 7 is a diagrammatic view illustrating an electrical circuit between individual switches and lamps controlled thereby.

In carrying out the invention I provide a plurality of similar elements one for each character or number which may be employed in a particular game with which the apparatus may be associated. These may be electric switches, each of which may control an indicator or indi-

40 cators which when actuated may denote one of a plurality of characters or numbers forming part of the game with which the selector may be employed. These indicators may be lamps having a designating number. For example, when the apparatus is to be employed in the game of "Bingo" for choosing the order of play, there will be one lamp for each numbered square.

45 In order to choose by chance which particular element will be actuated I arrange for a selector member such as a sphere, which upon release, will be free to move in any direction so that when guided by chance it will be moved to cause one of the control elements to be actuated.

With reference to the drawings for a more de-

tailed description of the invention, 10 designates generally an apparatus having a body portion 11. The body portion may be a frame of suitable shape and of any suitable material, that herein shown being circular in cross-section and cupped providing a top wall 12 inclined towards the center and an annular side wall 13 extending in a generally vertical direction. This body 11 may be cored as at 14 to lighten the same and may be supported on legs 15 attached thereto in a suitable manner.

Mounted to extend about the upper edge of the wall 13 are a plurality of similar units 17 operable to actuate means which indicate a particular character chosen or the order of play. In the present embodiment of the invention the means which indicate the chosen character or the order of play comprises electrical light bulbs, accordingly the unit 17 consists of electric switches of a toggle design wherein the contacts may be moved to open or closed position by a finger 18 which is reciprocally mounted in the body of the switch and with the end portions thereof extending beyond the body of the switch. A flange or arm 19 extends from the body of the switch into engagement with the outer side of wall 13 and is there secured by a screw 20. There is one switch for each character or number employed in the particular game with which the apparatus may be associated. These switches may be of any suitable approved design the details of which form no part of this invention.

In order to select any one of the switches 17 in the operation of the apparatus, a substantially conical shaped member 21 is provided. This member 21 is mounted to be above the wall 12 and centrally thereof with the outer edge 22 thereof adjacent to the fingers 18, of the switches. The member 21 is spaced from the body 11 by means of collars 23 and is secured in position by bolts 24 which extend through the body 11 and the collars 23 and are threadedly received in member 21. The upper side 25 of member 21 provides an inclined surface on which there may be moved by gravity the selector means to be positioned by chance at a location to be acted upon to operate any one of the switches 17. In order to enhance the degree of chance the side 25 is provided with a plurality of spaced protuberances 26 which are positioned so as to interrupt and change the direction of movement of the selector means which in the present instance is shown in the form of spheres 27.

The member 21 is further provided at the outer edge 22 with a wall 28 having a plurality of openings 29 (see Figs. 4 and 5). There is an opening opposite each switch and the side of each opening is provided with a flange 30. The upper edge of the wall is provided with bearings 31 which extend between each opening. Each opening 29 is closed to the free passage of a sphere 27 therethrough by means of a movably mounted plate or closure designated generally 32. Each closure comprises a flat sheet of stock bent intermediate the ends thereof so as to provide right angular extending portion 33 and 34 (see Fig. 3). A hinge pin 35 is attached to the portion 34 and is journaled in the bearings 31. The portion 34 is made of a double thickness or may be otherwise weighted so as to tend to swing the closure 32 about its mounting when free to move so as to position the portion 34 to close the opening 29 with which it is associated. In the initial position of the closure 32 at the beginning of a game, the portion 33 is positioned

to close the opening 29 and is retained in this closed position by the engagement thereof with the finger 18 of an adjacently positioned switch 17, thus forming a pocket P in which a sphere 27 may lodge.

There are a plurality of spheres 27 and these are elevated through a centrally disposed tube 36 to be released on the surface 25 for gravitational movement towards the wall 28. This tube 36 is journaled in bearing openings 37, 38 in body 11 and member 21 respectively and extends beyond the upper edge of the member 21 and the bottom of body 11. The upper edge of the tube 36 is provided with a lateral slot 39 which extends axially of the tube adjacent the side 25. The tube 36 is also provided with an opening 40 positioned therein adjacent the upper side of wall 12 and is of a size whereby the spheres 27 may pass into the tube. A plunger 41 is reciprocally mounted in the lower end of the tube to move the sphere 27 upwardly through the tube to be discharged through the slot 39.

The power source for rotating the tube 36 and for reciprocating the plunger 41 comprises in the present instance an electric motor 42 supported in a bracket 43 depending from the body 11. The shaft 44 of the motor is extended and is journaled in a bearing 45 and has mounted thereon a cam 46 which engages the plunger 41. A friction wheel 47 is secured to the shaft 44 and engages with a similar wheel 48 which is fast to the end of tube 36. In place of friction wheels 47, 48 gear wheels may be employed if so desired. It will be apparent that as the cam is rotated the plunger 41 will be reciprocated and the spheres 27 will be moved upwardly in the tube and be spilled through the slot 39 onto the wall 25. In order to provide for loading the tube with members 27, a resilient finger 49 is fastened to the tube and extends into the tube a distance sufficient to be engaged by the lower one of the spheres 27 as moved upwardly in the tube. This will retain the lower sphere in the tube in position above the opening 40 so as to permit another sphere 27 to enter the tube. The finger 49 is sufficiently flexible to be moved outwardly by a sphere 27 being pushed past the finger and there after snap into position to provide the stop as above described.

In presetting the apparatus prior to the beginning of a game the closures 32 are swung about their mountings in a direction to move the portion 33 to the closed position thereof. This is accomplished in the present embodiment by means of a ring designated generally 50. The ring is mounted to be moved axially of member 21 by means of spaced rods 51 which depend from the ring and slidably extend through openings 52 in the body 11. The rods extend beyond the body 11 and through brackets 53 which have openings 54 in line with openings 52 for receiving the rods. Each rod 51 is provided with a stop collar 55 which is adjustably secured thereto and which abuts against the body 11 when the ring is in the uppermost position. A compression spring 56 surrounds each rod between the collar 55 and the bracket 53. These springs are of sufficient force to move and hold the ring in proper position above the member 21. An annular flange 57 depends from the ring at a location to be engaged by the portion 33 of the closure member when moved to the opened position as shown at A in Fig. 1. A handle 58 is provided for axially moving the ring and this is attached to the ring by spaced arms 59. When

the ring is moved downwardly the flange 57 will engage the portion 33 and swing the closure 32 about its mounting in a direction to move the portion 33 to the closed position.

With the portion 33 in the closed position, the fingers 18 of switches 17 are moved by means of a ring 60 to open position and in which position the fingers 18 are closely adjacent to the portion 33 and hold them closed when the ring 50 is permitted to return to initial position. The ring 60 is mounted concentric with the ring 50 and is also mounted for axial movement by means of rods 61 depending therefrom and passing through openings 62 in bosses 63 provided on the outer side, of the body 11. Each rod has a collar 64 secured to the end thereof which engages the lower side of the boss 63 through which the rod is resiliently retained in the upper position by compression springs 65 acting against bosses 63 and collars 66 secured to the rods 61, so as to bias the collars 64 against the bosses 63. The inner wall 67 of the ring 60 is inclined or tapered outwardly with the lower edge thereof in line with the outer end of the finger 18 and positioned to be closely adjacent the fingers when the fingers are in the outward position. The outer edge of ring 50 extends beyond the inner edge of ring 60 and will engage and move the ring 60 therewith when moved to reset the portions 33. This action will cause such finger 18 engaged by the wall 67 to move inwardly by the wall 67 to reset the switch to open position.

With the apparatus properly pre-set the motor is set into motion which through the gearing 45, 48 will rotate the tube 36 and through the cam 46 reciprocate the plunger 41 to move the spheres 27 upwardly through the tube 36. A sufficient number of spheres 27 are provided for assuring the proper loading of the tube. At each cycle of the cam 46 a sphere 27 will be discharged through the slot 39 into the incline 25 and will be moved therein by gravity to the outer edge to lodge into or adjacent one of the pockets P. The depth of each pocket is such that a substantial portion of a sphere therein will extend outwardly of the pocket. In order to actuate the switch associated with the pocket P into which a sphere may have lodged an arm 68 is mounted on the upper end of the tube 36 so as to rotate therewith. The arm has a slot 39' similar to slot 39 and registers therewith. The arm extends generally parallel to the wall 25 and is of a length to extend closely adjacent to the wall 28. As the arm 68 is moved across the incline 25 the free end thereof will engage a sphere 27 lodged in a pocket P and move the same to pass through the pocket. This action will cause the portion 33 to be moved by the sphere which in turn will move the finger 18 in contact therewith. The distance the finger will be moved will be sufficient for the inner mechanism (not shown) of switches 17 to move the finger the required distance so as to close the contacts of the switch. Such movement of the finger 18 will provide sufficient space for the now free closure 32 to be swung about its mounting by means of the weighted portion 34. This will position the portion 34 to close the opening of the pocket to any subsequently moved sphere 27 and will be maintained in this position by the portion 33 engaging the flange 57 as at A. A sphere passing through a pocket 29 will drop on the inclined wall 12 and will gravitate towards the center of the wall 12 and into the tube 36 through the slot 40. It will be apparent that a sphere lodging between pockets will be moved by the arm and

lodged in a pocket. It will also be apparent that a sphere may be discharged from the tube on either side of the slot 39. Consequently the arm 68 may not engage the spheres in the order released thereby enhancing the chance of selection. In playing the game of "Bingo" with the apparatus herein described, each switch 17 will be placed in a circuit of a group of lamps having the same designation. There will be as many switches as there are groups of lamps. When a particular switch has been closed in the manner above described all lamps in the group in which the switch is placed will be lighted. For instance, in Fig. 7 lamps 70, 71 and 72 are in a group controlled by switch 73 the closing of which would light these lamps. Were another switch 74 selected, all lamps 75 would then be lighted.

I claim:

1. A game apparatus comprising a plurality of pockets positioned in spaced relation to each other and each having a movable rear wall, a surface inclined towards said pockets, said surface having a plurality of protruding elements, a movable member movable by gravity over said surface and guided by impact with said protruding elements for lodging by chance in one of said pockets and against the rear wall thereof, yieldable means movable to a position adjacent to said rear walls for holding said rear walls in the closed position against the impact of said movable member upon the movement thereof by gravity into one of said pockets, means for engaging and moving said movable member to move said rear wall and yieldable means and pass said member out of said pocket, and means including said yieldable means responsive to the movement of said rear wall to actuate an electric circuit, including a plurality of lamps.

2. A game apparatus comprising a plurality of pockets positioned in a circle in spaced relation to each other and each having a movable rear wall, a surface inclined towards said pockets, said surface having a plurality of protruding elements, a member movable by gravity over said surface and guided by impact with said protruding elements for lodging by chance in one of said pockets and against the rear wall thereof, means for engaging and moving said movable member to move said rear wall and pass said member out of said pocket, and means positioned to be engaged by and responsive to the movement of said rear wall to actuate an electric circuit, including a plurality of lamps.

3. A game apparatus comprising a plurality of pockets positioned in spaced relation to each other and each having a movable rear wall, an electric switch having a contact moving arm separate of said rear wall and normally in contact with said rear wall and movable thereby, a surface inclined towards said pockets, said surface having a plurality of protruding elements, a member movable by gravity over said surface and guided by impact with said protruding elements for lodging by chance in one of said pockets and against the rear wall thereof, and means for engaging and moving said movable member to move said rear wall and said contact moving arm thereby actuating an electric circuit and passing said member out of said pocket.

4. A game apparatus comprising a plurality of pockets each having a movable rear wall, a surface inclined towards said pockets, said surface having a plurality of protruding elements, a free movable member, means for positioning said member on said surface to be moved thereon

by gravity and guided by impact with said protruding elements for lodging by chance in one of said pockets and against the rear wall thereof, yieldable means movable to a position adjacent to said rear walls for holding said rear walls in the closed position against the impact of said movable member upon the movement thereof by gravity into one of said pockets, and means for engaging and moving said movable member to move said rear wall and yieldable means thereby actuating an electric circuit and passing said member out of said pocket.

5. A game apparatus comprising a plurality of pockets each having a movable rear wall, a surface inclined towards said pockets, said surface having a plurality of protruding elements, a free movable member, a conduit to the upper part of said surface, means for moving said member through said conduit to be discharged therefrom on said surface to be moved thereon by gravity and guided by impact with said protruding elements for lodging by chance in one of said pockets and against the rear wall thereof, yieldable means for holding said rear wall in the closed position against the impact of said movable member upon the movement thereof by gravity into one of said pockets, means for engaging and moving said movable member to move said rear wall and yieldable means thereby actuating an electric circuit and passing said member out of said pocket, and means for returning said member to said conduit.

6. A game apparatus comprising a plurality of pockets each having a movable rear wall, a surface inclined towards said pockets, said surface having a plurality of protruding elements, a free movable member, a conduit to the upper part of said surface, means for moving said member through said conduit to be discharged therefrom on said surface to be moved thereon by gravity and guided by impact with said protruding elements for lodging by chance in one of said pockets and against the rear wall thereof, yieldable means for holding said rear wall in the closed position against the impact of said movable member upon the movement thereof by gravity into one of said

pockets, means for engaging and moving said member to move said rear wall and yieldable means and pass said member out of said pocket, and means for returning said member to said conduit, and means including said yieldable means responsive to the movement of said rear wall to actuate an electric circuit including a plurality of lamps.

7. A game apparatus comprising a plurality of pockets each having a movable wall, an electric switch having an operating arm extending therefrom and movably mounted thereon, said arm being normally in contact with said movable wall and moved thereby to actuate said switch, a surface inclined towards said pockets, said surface having a plurality of protruding elements, a member movable by gravity over said surface and guided by impact with said protruding elements for lodging by chance in one of said pockets and against the movable wall thereof, said wall being held in the closed position by said arm against the impact of said movable member upon the movement thereof by gravity into one of said pockets, means for engaging and moving said member to move said movable wall and said operating arm thereby actuating an electric circuit, and means movable into position to block the entrance to the said one of said pockets upon the moving of said movable wall.

8. A game apparatus as set forth in claim 1 wherein said surface is substantially in the form of a truncated cone.
